Lawrence F. Erskine, 3440 46th Avenue S.,
Minneapolis, Minn.

Filed Aug. 26, 1964, Ser. No. 81,454

Term of patent 14 years

(Cl. D30—1)

FIG. 1

FIG. 3

FIG. 2

FIG. 4

FIGURE 1 is a front elevational view of a lead sight for guns showing my new design, the view also constituting a rear elevational view because of the symmetry of the sight;

FIGURE 2 is a top plan view of the sight shown in FIGURE 1;

FIGURE 3 is a side elevational view taken from either side of the sight as shown in FIGURE 1, and

FIGURE 4 is a bottom plan view of FIGURE 1.

I claim:

The ornamental design for a lead sight for guns, as shown and described.
